UNITED STATES PATENT OFFICE.

WILLIAM SHAKESPEARE, JR., AND WILLIAM SCHMID, OF KALAMAZOO, MICHIGAN,
ASSIGNORS TO WILLIAM SHAKESPEARE JR. COMPANY, OF KALAMAZOO, MICHIGAN.

CARBURETER.

1,129,129.

Specification of Letters Patent. Patented Feb. 23, 1915.

Application filed February 27, 1911. Serial No. 611,064.

To all whom it may concern:

Be it known that we, WILLIAM SHAKESPEARE, Jr., and WILLIAM SCHMID, citizens of the United States, residing at Kalamazoo, Michigan, have invented certain new and useful Improvements in Carbureters, of which the following is a specification.

This invention relates to improvements in carbureters.

10 The main objects of this invention are: First, to provide an improved carbureter, in which the proper relative proportions of the fuel and air are maintained. Second, to provide an improved carbureter, in which 15 the quantity of the fuel delivered may be accurately controlled. Third, to provide an improved carbureter, in which the air or throttle valve and the fuel valve are simultaneously operated. Fourth, to provide in 20 the carbureter an improved structure which is not likely to get out of adjustment or repair in use. Fifth, to provide in an improved carbureter a valve mechanism which can be adjusted for convenient attachment to 25 the operating connections.

Further objects, and objects relating to structural details, will definitely appear from the detailed description to follow.

We accomplish the objects of our invention by the devices and means described in the following specification.

The invention is clearly defined and pointed out in the claims.

A structure which is a preferred embodiment of our invention is clearly illustrated in the accompanying drawing, forming a part of this invention, in which:

Figure I is a side view of a structure embodying the features of our invention. Fig. II is a central longitudinal section through the structure shown in Fig. I. Fig. III is a horizontal section taken on a line corresponding to line 3--3 of Fig. II. Fig. IV is a detail horizontal section taken on a line corresponding to line 4--4 of Fig. II. Fig. V is an inverted perspective view of the body member 16, the fuel valve and air valve being shown in operative relation thereto. Fig. VI is a detail perspective view of the throttle or air valve. Fig. VII is an inverted perspective view of the valve member 19. Fig. VIII is a detail section corresponding to Fig. IV of a slightly modified structure.

55 In the drawing, similar reference charac-

ters refer to similar parts throughout the several views, and the sectional views are taken looking in the direction of the little arrows at the ends of the section lines.

Referring to the drawing, the carbureter 60 body 1 is provided with an air passage 2, adapted for connection to the engine cylinder, the connections not being here illustrated as they will be readily understood. In the bottom of the air passage 2 is a cavity 65 3. This cavity is partially closed by a block-like member 4, having groove-like passages 5 therein. This is for convenience in manufacture as the passages 5 might be otherwise formed. These passages form a by pass 70 70 passage around the throttle valve as will appear as the description proceeds. This by pass passage is connected to the fuel reservoir 6, by means of the passage 7.

The fuel feed reservoir is connected to a 75 suitable source of supply by the pipe 8, the delivery passage 9 of which is controlled by valve 10, the valve being controlled by the float 11. The details of this valve and its connection to the float, form no part of the 80 present invention and are therefore not described with further detail herein. The fuel reservoir is formed of a cylindrical body portion 6, preferably of glass, as shown, the base portion 12 and disk-like top 13, the 85 body 1 being shouldered to receive the top, all the parts being clamped together by the coupling member 14, as shown in detail in Fig. II. This construction greatly facilitates manufacture and makes it possible to 90 finish the parts as may be desired.

The body for convenience in manufacturing and assembling of parts is provided with an opening 15 opposite the fuel passage. This opening is closed by the body 95 member 16, the member being detachably secured as by means of the screws 17. The fuel valve 18 is of the needle type and seats into the upper end of the part 7 of the fuel feed passage, it being shown in Fig. II, in 100 its completely closed or seated position. The valve 18 is threaded into the valve member 19, which is in turn threaded for adjustment into the body member 16. A spring washer 20 is disposed between the 105 valve member 19 and the body member 16 to take up any slack or lost motion in the threads. The valve member 19 is adapted to receive the valve lever 21, which is adjustably secured upon the upper end there- 110

of by means of the screw 22, the head of the lever being split and provided with ears 23 through which the screw is arranged.

5 Mounted on the valve above the valve lever is an index disk 24 as shown in Fig. III, to facilitate the accurate adjustment of the valve, the disk being rotatably secured to the valve which is flattened at its upper end as shown in Fig. II.

10 A clamping nut 25 is provided for locking the valve in its adjusted position in the valve member 19. The valve member 19 is provided with stops 26 and 27 which coact with the stop 28 on the body member 16.

15 The stop 26 is adapted to locate the valve in its open position and the stop 27 locates it in its closed position. The stop 27 is made adjustable so as to determine the closed position of the control valve as shown in Fig. VI. The valve 29 is provided with a hub portion 30 through which the valve 18 is arranged. The valve 29 is operatively connected with the valve member 19, by

20 means of the lugs 30' on the valve which engage notches 31 in the lower end of the valve member. This loose connection for the fuel and throttle valves permits the adjustment of the throttle valve and its longitudinal movement, while the throttle valve 25 has a rotary or oscillating movement.

30 It will be observed that the passage 5 forms a by-pass or auxiliary air passage around the air valve. This, when the air passage is closed, or partially closed, causes 35 a direct stream of air to pass through passage 5, breaking up or atomizing the fuel very effectively. This fuel can be very accurately controlled by the adjustment of the valves. By providing this by-pass or auxiliary air passage around the air or throttle valve in communication with the fuel supply, the increased suction caused by closing or partially closing the throttle acts directly on the fuel to effectively break up or 40 atomize the same.

45 For convenience in manufacturing parts, the body member 16 is provided with opposed side members 32 which are located in recesses 33 in the body.

50 The valve 29 is located between these parts 32. By forming the body with the opening 15 and mounting the valves on the closure 16, the parts may be readily assembled or disassembled and are simple in structure.

55 In order to maintain the relative proportion of the air and fuel throughout the movement of the control valve 29, we form vertical curved grooves or channels 32' in the 60 faces of the side members 32 of the body member 16. For some engines, these are not needed, and the said members 32 are then formed with flat faces, as shown in the modified structure of Fig. VIII. These 65 grooves 32' can be readily milled into the

body member 16, or it can be left with flat faces, as shown in Fig. VIII.

The fuel reservoir is provided with a drain valve which consists of a nipple-like valve casing 34, having a valve seat 35 at its inner end, its outer end being threaded to receive the valve stem 36 of the valve 37. The valve stem is provided with a passage 38 having lateral inlets 39 to the rear of the valve. To open the valve it is only necessary to screw it out sufficiently to draw the valve slightly from its seat and the liquid will pass around the valve into the passage of the stem.

We have illustrated and described our improvements in a simple embodiment thereof.

We are aware that various changes or modifications in structural details are possible, but as such modifications or changes will no doubt be readily understood by those skilled in the art to which this invention relates, we have not attempted to illustrate or describe the same herein.

Having thus described our invention what we claim as new and desire to secure by Letters Patent is:

1. In a carbureter, the combination of a valve actuating member having threaded engagement with its support; a fuel valve threaded through said valve actuating member; an index disk for said fuel valve mounted to be adjusted therewith; a fixed stop; coacting stops on said valve member, one of which is adjustable; and a throttle valve loosely mounted on said fuel valve for longitudinal movement thereon and operatively connected with said valve actuating member.

2. In a carbureter, the combination of a valve actuating member having threaded engagement with its support; a fuel valve threaded through said valve actuating member; an index disk for said fuel valve mounted to be adjusted therewith; a fixed stop; and coacting stops on said valve member, one of which is adjustable.

3. In a carbureter, the combination with the body provided with an air passage and a fuel passage, said body having an opening opposite said fuel passage; a closure member for said opening; a valve actuating member operatively threaded into said closure member; a fuel valve threaded through said valve member to project through said air passage into said fuel passage; an index disk for said fuel valve arranged thereon above said valve member; and an air passage valve loosely mounted on said fuel valve for longitudinal movement and being operatively connected to said valve.

4. In a carbureter, the combination with the body provided with an air passage; a valve actuating member having threaded engagement with its support; a fuel valve threaded through said valve actuating member; and a throttle valve loosely mounted on

- said fuel valve and having operative connection with said valve actuating member.
5. In a carbureter, the combination with the body provided with an air passage and a fuel passage, there being an opening in the body opposite the fuel passage; a body closure member having opposed side portions seated in recesses provided therefor in the walls of the said air passage; and a throttle 10 valve arranged between the sides of said body member, said sides being provided with vertical channels curved in cross section.
6. In a carbureter, the combination with the body provided with an air inlet passage 15 and a fuel passage, there being an opening in the body opposite the fuel passage; a body closure member having opposed side portions seated in recesses provided therefor in the walls of the said air passage; and a throttle valve arranged between the sides of 20 said body member.
7. In a carbureter, the combination with the body having an air passage and a fuel passage therein; a fuel reservoir comprising 25 a top plate, said body being shouldered to receive said plate, a cylindrical body portion, a bottom engaging said body, and means for clamping said parts together.
8. In a carbureter, the combination with
- the body having an air passage and a fuel 30 passage therein; a fuel reservoir comprising a top plate and body portions, said body being shouldered to receive said plate, and means for clamping said parts together.
9. In a carbureter, the combination of a carbureting chamber, a fuel supply passage, 35 a fuel control valve, a throttle valve for said carbureting chamber, a butterfly throttle valve for said carbureting chamber loosely mounted on said fuel control valve and having operative connections therewith, and an air by-pass passage for said throttle valve 40 communicating with said fuel valve and delivering at the rear of the throttle valve when the throttle valve is closed, said by-pass passage constituting the delivery passage for the fuel passage to the carbureting chamber, the fuel valve being disposed to control the delivery of fuel to the said air 45 by-pass passage.

In witness whereof, we have hereunto set our hands and seals in the presence of two witnesses.
